UNITED STATES PATENT OFFICE.

CHARLES L. MEYER, OF OMAHA, NEBRASKA.

CONCRETE FLOOR CONSTRUCTION.

1,262,686.

Specification of Letters Patent. Patented Apr. 16, 1918.

Application filed March 6, 1917. Serial No. 152,544.

To all whom it may concern:

Be it known that I, CHARLES L. MEYER, a citizen of the United States, residing at Omaha, in the county of Douglas and State 5 of Nebraska, have invented certain new and useful Improvements in Concrete Floor Constructions, of which the following is a specification.

This invention relates to the general art 10 of concrete building structures, and has reference more particularly to improvements in concrete floors for buildings. Those familiar with the art of concrete floor construction are aware that the floor proper is supported by girders, which in turn are connected sidewise by a series of joists beneath the floor, the girders, joists and overlying floor being formed integrally of concrete, and the girders commonly having metal reinforcing 15 rods lying in and lengthwise of the lower or tension region thereof. The forms or molds usually of a generally inverted U shape, over which the concrete is poured, extend from girder to girder and are so positioned with 20 respect to each other that the joists are formed between adjacent sides of the spaced rows of forms, the end form of each row having a vertical or substantially vertical end wall which provides a portion of the 25 side wall of the girder mold. A construction of this character is typically illustrated in Letters Patent of the United States No. 1,106,665, granted to me August 11, 1914, although in the said patent the girders are 30 shown as having I-beam reinforcements and the joists as having tension-rod reinforce- 35 ments.

My present improvements are more particularly, although not exclusively, designed 40 and adapted for constructions employing solid concrete girders, with or without tension-rod reinforcements; and one of the objects of the invention is to provide a combined integral concrete floor, girder and joist 45 construction of such a form that the girders, joists and floor proper will be reinforced at their points of junction to resist shear strains without using an excessive or unnecessary amount of concrete or reinforcing 50 metal. Another object of the invention is to provide an improved juncture of both the floor proper and the joists with the girder, which, through a more scientific distribution 55 of the concrete, will combine equal or greater strength with an economy in the amount of concrete heretofore used. As will appear

from the following detailed description and the drawing, the objects are attained by a construction wherein the joists are gradually widened as they merge into the girder, and 60 the floor proper is gradually thickened as it merges into the girder.

The structure and advantages of the invention will be readily understood and appreciated by building engineers and others 65 skilled in the art from the following description, taken in connection with the accompanying drawing, wherein—

Figure 1 is a fragmentary top plan view of a concrete floor construction embodying my 70 invention, the same being broken out and in horizontal section at the point of juncture of two of the floor joists with the girder;

Fig. 2 is an enlarged vertical section taken on the line 2—2 of Fig. 1; 75

Fig. 3 is a vertical section at right angles to that of Fig. 2, and taken on the line 3—3 of Fig. 2; and

Fig. 4 is a perspective detail, partly broken out, of an end form or mold through 80 the agency of which the improved construction is obtained.

Referring to the drawing, 5 designates the floor proper, 6 the girders, and 7 the joists of my improved floor structure, all of these 85 elements constituting an integral or one-piece structure of solid concrete, with reinforcing tension rods 8 preferably employed in the tension region of the girders, as common in this type of structure. By reference to Figs. 1 and 3, it will be observed 90 that the end portions of the joists 7 are gradually widened horizontally for some distance as they approach and merge into the sides of the girders 6, such widened end 95 portions being indicated by the reference numeral 7'. By reference to Figs. 2 and 3, it will also be observed that the portions of the floor 5 lying between adjacent joists are gradually thickened vertically for some distance as they approach and merge into the upper portion of the girder, such thickened 100 floor portions lying wholly above the neutral axis of the latter and being indicated by the reference numeral 5'.

A simple and practical means by which the described conformation may be produced is a tapered end mold section such as is shown in perspective detail in Fig. 4 and in longitudinal and transverse section in Figs. 110 2 and 3, respectively. This end section, it will be observed, is formed with side walls

8 which converge toward the vertical end wall 9 and also gradually decrease in height toward the latter, so that the top wall 10 of the mold section is downwardly inclined 5 toward the end wall 9, as clearly shown in Fig. 2. The convergent taper of the side walls 8 produces the widened end formation 7' of the joist molded between two laterally adjacent end sections; while the downward inclination or taper of the top wall 10 produces the gradually thickened floor portion 5' between adjacent joists and lying next to the girder; but this thickening and reinforcing of the floor structure is accomplished without any increase, but rather with a decrease, in the quantity of concrete used, for the reason that the end form of the mold is extended inwardly into substantial vertical alinement with the side of the lower 20 portion of the girder, thereby eliminating the lower portion of the cap or shoulder of the T girder that lies below the neutral axis of the latter, and which is practically valueless for strength purposes. An example of 25 a solid concrete T girder having such a shoulder on either side of the main body of the girder may be seen in Figs. 3 and 6 of Letters Patent to Dale, No. 1,131,479, March 9, 1915, this being the common and usual 30 form of solid concrete girder employed where steel I-beams are not used as the chief load-carrying element of the girder. My invention enables a solid concrete girder to be used, and yet eliminates a considerable 35 amount of useless concrete below the neutral axis, and at the same time, through the thickening of the floor proper at its region of juncture with the girder, offers an increased resistance to shear strains and also 40 reinforces the upper or compression region of the girder by giving to the latter a special T-form in cross section characterized

by a gradually increasing thickness of the cap portions as they merge into the body, as seen in Fig. 2. The described widening of 45 the joists where they merge into the sides of the girder also affords an increased resistance to shear strains at these points.

It should be manifest from the foregoing that my invention provides a concrete floor 50 construction of maximum strength to withstand shear strains by reason of the tapered enlargement of the joists and floor proper at their junctions with the girders. This increase in thickness of the joists and the 55 floor itself along the girders materially strengthens the entire structure, and requires less concrete than the known construction employing the shouldered form of solid concrete girder above referred to. 60

It is believed that the structure of my invention and the advantages inhering therein will be understood from the foregoing without further description; and, while I have shown and described the preferred embodiment of the invention, it should be obvious that the details of shape and proportions are capable of modification and variation within the scope of the invention as defined in the following claim. 70

I claim:

A combined T-girder, joist and floor construction formed integrally of concrete, and wherein the end portions of the joists lying beneath the cap of the girder are of gradually increasing width and decreasing depth as they merge into the stem of the girder, and the floor portions which merge into and define the cap of the girder lying above and between said end portions of the joists are 75 of gradually increasing thickness as they approach the stem of the girder and lie wholly above the neutral axis of the latter. 80

CHARLES L. MEYER.
